HENRY W. KETCHAM, OF NEW YORK, N. Y.

Letters Patent No. 102,129, dated April 19, 1870.

IMPROVEMENT IN STOPPERS FOR JARS AND BOTTLES.

The Schedule referred to in these Letters Patent and making part of the same

I, HENRY W. KETCHAM, of the city, county, and State of New York, have invented an Improvement in Stoppers for Fruit-Jars and other Bottles, of which the following is a specification.

The nature of my invention consists of a stopper formed with a conical or upwardly-beveled body, the smaller portion of which terminates in an abrupt shoulder, in combination with an annular cylindrical packing-ring of India rubber or other elastic material, said stopper being adapted for use with any unshouldered or smooth-mouthed bottle, jar, can, or other similar vessel.

In the drawings—

Figure 1 represents the stopper removed, the ring being shown in section.

Figure 2 shows the ring in plan view.

Figure 3 represents the stopper as applied in sealing a jar or bottle, the latter with the packing-ring shown in section.

The stopper A is preferably constructed of glass, but any other suitable material may be used.

The conical portion a and the flange b b are of smaller diameter than the neck of the bottle in which they are to be used, and the ring c is of such size as to clasp the conical body with sufficient force to retain its position on the stopper when not inserted in the jar, and of such thickness that its external diameter is considerably greater than that of the mouth of the jar, so that, when inserted, it is so compressed as to flatten and extend it so as to cover the whole or a greater part of the conical part a, and also compress it closely into the angle between said part and the abrupt shoulder of the flange b.

It thus forms an extended joint or surface, in contact with both the sides of a and the interior of the mouth or neck of the bottle, as shown at c' c' in fig. 3, which more effectually excludes the air.

The necks of most jars and bottles are slightly ta-

pering, being largest at the mouth. This form facilitates the insertion of my improved stopper, but is not essential, as it fits equally tight if the neck is not tapering, after sufficient force has been used to drive it in.

The action of pushing the stopper in first compresses the ring against the shoulder b, when its elasticity causes it to extend downward in the narrowing interstice, until an equilibrium exists between the two extremities, which correspond in form and action to a wedge, the lower being the point and the upper the head, driven in and held by the flange or shoulder b.

It is withdrawn with comparative ease, on account of the cylindrical form of the packing-ring, which rolls as the stopper comes out, and may, if the resistance is great, be disconnected from it, the parts in such case being separately removed, and the ring again placed on the stopper for subsequent use.

The stopper is capable of repeated service, the use not being injurious to it in any manner, and it is designed to be manufactured and sold separately from the jars, of assorted sizes adapted to the usual range of different-sized bottles, its construction being such as to insure a suitable fit of the same stopper with considerable variation in the size of the neck of the bottles.

I claim as my invention—

An improved bottle-stopper, formed of the conical-shouldered stopper or plug A and cylindrical packing-ring c, constructed and operating substantially as set forth.

In witness whereof I have hereunto signed my name in the presence of two subscribing witnesses.

HENRY W. KETCHAM.
